UNITED STATES PATENT OFFICE.

CLARENCE E. SACKETT, OF GARDEN PRAIRIE, ILLINOIS.

IMPROVEMENT IN TAGS.

Specification forming part of Letters Patent No. **222,954**, dated December 23, 1879; application filed June 13, 1879.

To all whom it may concern:

Be it known that I, CLARENCE E. SACKETT, of Garden Prairie, in the county of Boone and State of Illinois, have invented a new and Improved Tag, of which the following is a specification.

Figure 1 represents the tag ready for the attachment of eyelet, cap, and wire. Fig. 2 represents the wire ready to be attached to the tag. Fig. 3 is an elevation of the eyelet. Fig. 4 is a plan of the cap. Fig. 5 shows the manner of securing the wire to the tag. Fig. 6 shows the tag completed.

Similar letters of reference indicate corresponding parts.

The object of this invention is to provide a more simple, perfect, convenient, and durable wired tag than any now in use.

The invention consists in securing the wire to a tag in a novel manner, and so that it will not cut it, and so that the tag will lie flat and not turn edgewise when attached to any article.

A is the blank of the tag, of paper, stout cotton, linen, or other fabric, with two corners cut off, as shown at *a' a'*, a crescent-shaped opening, *b'*, and two corresponding holes, *c' c'*. B is a metallic eyelet; C, a cap of paper or other flexible material; D, a flexible wire bent in shape for attachment to the tag-blank.

The further process of manufacture consists in setting the cap over the eyelet, and then inserting the smaller end of the latter through the hole in the body of the tag-blank, and in then inserting the loop of the wire through the crescent-shaped aperture and over the projecting end of the eyelet, as shown in Fig. 5; then the flap *d'* of the blank is turned down and the hole in it pressed over the eyelet, and finally the tag is put in an eyelet-press that spreads and presses the eyelet down, so as to secure the parts firmly together, when the device appears as shown in Fig. 6.

The cap C furnishes a bearing for the head of the eyelet, and thereby renders the eyelet less liable to be torn out than if the head of the eyelet came in direct contact with the tag, and it is, preferably, not glued or pasted

to the tag, in order to render it more flexible at that point.

In all wired tags heretofore used, the wire passes through the eyelet inserted in the end thereof, and hence it must be twisted close to the tag in order that it may retain its place, and in twisting the wires the tag is frequently torn and injured.

In printing on tags the twisted wire is much in the way, as it will not permit the tags to lie flat, nor is it so flexible and easily attached to any article as is the single wire herein shown.

All these and other objections to the wired tags now in use are obviated by my device of attaching the wires by bending them around the shank of the eyelet between the folds of the tag, and permitting their ends to project straight out through the crescent-shaped opening in the fold.

Another advantage possessed by this tag is, that it is much more flexible, and consequently not so readily torn or broken in ordinary usage, where the wire is secured to it, because the cap is separate from it, *i. e.*, not glued or pasted to it in the usual manner, nor is there any metal cap with points penetrating the tag to make it especially liable to break at that point.

I do not confine myself to an eyelet separate from the cap, or to a cap of paper or other fabric, because cap and eyelet in one piece, and of metal or other material, may be used without departing from my invention; but

Having thus described my invention, I claim as new and desire to secure by Letters Patent—

As a new article of manufacture, the within-described tag, consisting of the tag-blank A, with eyelet B and cap C, and wire D, bent around the shank of the eyelet, the said eyelet serving the double purpose of securing the wire to the tag, and the flap of the tag to the body of the same, substantially as herein shown and described.

CLARENCE E. SACKETT.
